UNITED STATES PATENT OFFICE.

CARL BARR, OF CHICAGO, ILLINOIS.

SPRING TERMINAL CLIP.

1,078,766.

Specification of Letters Patent. Patented Nov. 18, 1913.

Application filed April 5, 1913. Serial No. 759,093.

To all whom it may concern:

Be it known that I, CARL BARR, a citizen of the United States, and a resident of Chicago, Illinois, have invented certain new and useful Improvements in Spring Terminal Clips, of which the following is a specification.

The essential object of this invention is to provide a spring terminal clip or fastening device for the terminals of electric conductors, and the invention is designed to enable the conductor to be firmly gripped and clamped in any desired position allowing the conductor to be readily inserted and removed and yet at the same time insuring good electrical contact at all times between the conductor and the terminal clip.

In the drawings, Figure 1 is a perspective view of a fastening device embodying the invention; Fig. 2 is an end elevation of the device shown in Fig. 1; Figs. 3 to 6, inclusive, are views of sundry modifications of the invention; and Fig. 7 is a view of the form shown in Fig. 6 with the conductor applied thereto.

The terminal-clip is preferably made of a single piece of resilient material, sheet metal being preferred, and is so constructed that all the parts of the terminal-clip are integrally united together and yet without permitting any tongues or fingers attached to the main body of the clip at one end only.

The invention comprises two oppositely disposed members which are normally separated from each other, each of said members being adapted to co-act with each other in order to clamp a conductor in position when said members are forced into operative position. The resilient material is bent so as to bring one of said members opposite the other, the two members being connected.

In that form of the invention best shown in Figs. 1 and 2, the base 1 supports the terminal-clip which is formed of the two substantially vertical sections 2 and 3, said vertical sections 2 and 3 being joined together by the horizontal web 4. A screw 5 passes through the horizontal web 4 and clamps the clip to the base 1. The arm 3 is substantially V-shaped at its outer edges, the apex 6 of the V pointing toward the right in said Figs. 1 and 2. At about the middle of said member 3, a ribbon or web 7 is stamped out, said ribbon or web being also substantially V-shaped and with its apex 8 turned toward the left. The ribbon 7 is formed in-

tegrally with the rest of the member 3 and is secured thereto at both ends. The member 2 is the converse of the member 3, being provided with a V-shaped portion and two W-shaped portions, it being understood that the term W-shaped applies as well to the ribbon 7 and that part of the member 3 above and below the ends of the ribbon. The V-shaped ribbon 9 of the member 2 is adapted to project through the slot or opening 10 and to seat in the crotch or apex 8 of the ribbon 7. The opening 10 is the opening which is left in the member 3 after the tongue 7 is stamped out. The ribbon 9, like ribbons 7, has its apex turned toward the left, and those members 11 and 12 of the member 2 which together with the top and bottom of said member form the W, have their central apexes turned toward the right, the apexes of the V on member 3 being adapted to seat within the corresponding apexes of the members 11 and 12.

In Fig. 1 the parts are shown in the positions respectively assumed by them before the conductor is grasped by the clip, but when the clip is to be used the members 2 and 3 are pushed toward each other so that the tongue 9 will project through the perforation 10. The conductor 13 is then placed in the position shown in Fig. 3, and when the fingers of the operator are removed, the resilience of the members 2 and 3 will cause the same to clip or grasp the conductor 13 which is held engaged by the right-hand surface of the ribbon 9 and by the left-hand surface of the V-shaped part of the member 3.

The modifications shown in Figs. 3, 4, 5, and 6, require no special description as the same are merely suggestive of numerous changes in the invention. The insulation may extend to a point closely adjacent the terminal clip or may be omitted altogether if desired.

It is obvious that many changes in the details of construction and arrangement of parts may be made without departing from the scope of the invention.

I claim as my invention:

1. A clip comprising two oppositely-disposed and normally-separated members, each of said members being V-shaped and being provided at its apex with a recess formed by cutting out a ribbon, which said ribbon is also V-shaped, its apex projecting in a direction opposite to the apex of said mem-

ber, both ends of said ribbon being secured to said member, the V-shaped apex of one of said members being adapted to project into the recess thus formed on the opposite member, and to engage the projecting V-shaped ribbon upon said opposite member, the V-shaped apex on one member and the V-shaped ribbon upon the other member being adapted to grasp a wire or similar article between them.

2. A clip comprising two oppositely-disposed and normally-separated members, each of said members being V-shaped and having a ribbon stamped out of each, which said ribbon is secured at both ends to the member out of which it is formed, each of said ribbons extending in a direction opposite to the adjoining portion of the member of which said ribbon is formed, the projecting ribbon upon one of said members being adapted to enter the recess formed by cutting out the ribbon upon the other of said members and to engage said other ribbon, the ribbon upon one of said members and

the main body portion of the other of said members being adapted to grasp a wire or similar article between them.

3. A clip comprising a pair of body members in spring-like relation to each other, each of said members having a V-shaped portion formed out of the body of said member, said V-shaped portions being secured at both ends to the members out of which they are respectively formed, one of said V-shaped portions being adapted to project into the recess formed by the other of said V-shaped portions, said V-shaped portions being adapted one to receive the other, one of said V-shaped portions and the main body of said member being adapted to grasp a wire or similar article between them.

In testimony whereof I hereunto affix my signature in the presence of two witnesses.

CARL BARR.
